POLE FITTING

Ralph R. Pittman, Pine Bluff, Ark.

Application June 17, 1935, Serial No. 27,063

1 Claim. (Cl. 248—65)

This invention relates to devices for supporting overhead electrical conductors on pole lines.

The present invention is a continuation in part to my co-pending application for Conductor support, Serial No. 1,707, filed January 14, 1935 which has matured into Patent No. 2,022,386 of November 26, 1935.

The principal object of this invention is the provision in a one-piece fitting of a combination conductor support and guy attachment. The conductor support employed in this invention is substantially the same as that described in the above mentioned application.

Another object is to provide in such a combination a suitable place for retaining a conductor while it is being strung and pulled to tension.

An additional object is the provision of a simple and inexpensive fitting having the above mentioned advantages.

With these and such other objects in view as appear from the description, my invention resides in the particular form of construction of the fitting which enables it to be used for the several purposes above set forth.

In the drawing; Fig. 1 illustrates the fitting in the service position on a wood pole; Fig. 2 is a plan view of the fitting; Fig. 3 is a side elevational view; Fig. 4 is a sectional view of the device along the plane IV—IV of Fig. 2; and Fig. 5 is an end elevational view of the fitting.

Referring in particular to Figs. 2, 3, 4, and 5, the shank 17 is provided with threads at one end, and an integral base 12 at the other. As a desirable but not essential modification, the shank may be squared adjacent the base 12, as indicated by the numeral 16, to retard rotation of the fitting about the axis of the shank 17. Integral with the base and extending outwardly therefrom is an upwardly turned hook portion comprising the stem 13 and the enlarged upper portion 11. The latter is provided with the horizontally disposed circumferential flange 14, and the wire-receiving groove 15, which extends across the top of the enlarged upper portion 11 in a direction substantially normal to the shank 17.

Fig. 1 illustrates the device (here designated in its entirety by the numeral 10) installed on the pole 22, and held in place by the nut 18. The

guy wire 24 engages the upper convex surface of the stem 13, and has one end thereof secured in the usual manner by the clamp 25. The line conductor 19 extends across the wire-receiving groove 15, and the tie wire 20 cooperates with the flange 14 as required to provide a secure tie. To provide a tight tie, it is necessary that the bottom of the groove 15 be positioned at least not below the lower edge of the flange 14.

The numeral 23 indicates the device disclosed in my above mentioned application, and is here shown only to illustrate the manner in which the present invention may cooperate with this or similar fittings, as by providing means for attaching the conductor 21 to the opposite side of the pole 22.

During the process of installation of a conductor on a pole line provided with the fitting described herein, the conductor may be laid upon the stem 13 and drawn thereover as it is pulled to final tension. The upper surface of the stem is convexly curved to assure that the conductor will not be damaged when this is done; also to provide a smoothly curving surface for engaging a guy wire where necessary.

The fitting herein described may be economically produced as a steel drop forging, or may be cast from some suitable metal.

Other embodiments of the invention may appear from the one specifically described and illustrated herein, but it is to be understood that my invention will be limited only by the appended claim and the prior art.

I claim as my invention:

A pole fitting for supporting an overhead conductor comprising in a single piece of metal a shank, a base portion at one end of said shank, an upwardly turned hook portion including a stem merging with said base at one end thereof and an enlarged end portion at the other end of said stem, said enlarged portion having a horizontally positioned peripheral flange extending outwardly from the upper portion of said enlarged end portion and a substantially semi-circular conductor-receiving groove extending transversely thereacross in a direction normal to the axis of said shank.

RALPH R. PITTMAN.
